UNITED STATES PATENT OFFICE.

WILLIAM ARTHUR, OF NEWPORT, KENTUCKY.

IMPROVEMENT IN STEAM-PUMPS.

Specification forming part of Letters Patent No. 130,890, dated August 27, 1872.

To all whom it may concern:

Be it known that I, WM. ARTHUR, of Newport, in the county of Campbell and in the State of Kentucky, have invented certain new and useful Improvements in Steam-Pump; and do hereby declare that the following is a full, clear, and exact description thereof, reference being had to the accompanying drawing and to the letters of reference marked thereon making a part of this specification.

The nature of my invention consists in the construction and arrangement of a steam-pump, as will be hereinafter more fully set forth.

In order to enable others skilled in the art to which my invention appertains to make and use the same, I will now proceed to describe its construction and operation, referring to the annexed drawing, in which—

Figure 1 is a longitudinal vertical section, showing a horizontal pump. Fig. 2 is a similar section, showing a perpendicular pump. Fig. 3 shows a modification of the horizontal pump; and Figs. 4, 5, and 6 are attachments to be used in my pump.

A represents the pump-head, which is cast hollow, and may be globe-shape or any other convenient shape. B is the throat, which passes centrally across the water-chamber near to the steam-jet pipe C. This pipe may be screwed into the rear end of the head or cast in it, as most convenient. On the under side of the head A is an opening for the pipe D to be screwed into the head. On the front end of the pipe B is screwed a larger pipe, B', as shown in Fig. 1. A suitable steam-pipe connects the steam-jet pipe C with the boiler or any other suitable place where steam can be taken from. This steam-pipe must have a valve, a, to regulate the amount of steam and to stop and start it. In a perpendicular pump, as shown in Fig. 2, the head A' is pipe-shaped. On the side of the head is an opening for a steam-jet pipe, C, to enter in the side of the head; or this pipe may be cast in the head, as may be convenient. The end of the head A', toward the water, is much larger than the upper end at the throat B, the throat having an unvarying diameter, and discharging into a larger pipe, B. Steam-pipe and valve are provided the same as in the perpendicular pump.

In pumping water through hose with steam acting direct on the water it often becomes heated. To prevent the heating of the water

I use a cooler, E, of cylindrical, square, or other suitable shape, and pass the pump-pipe B' through water inside of the same. The cooler E may be attached to the bottom of a boat—that is, in the hold of the boat—or to the side on the inside, and must be placed below the surface of the water outside of the boat. The cooler E is connected, by hollow legs G G, with the bottom of the boat, holes being made in the same for the water to pass through said legs into the cooler. The pump, whether horizontal or perpendicular, is attached in like manner to the bottom of the boat.

To put the pump in operation, turn the valve a so that the steam will enter at the pipe C. The steam then forces the water through the pipe or throat B into the pipe B', and thence discharges it into other pipes or hose at pleasure.

H, I, and J are attachments to be used for the purpose of reducing the opening in the throat B, and by the reduction of said opening it will throw with a less amount of steam, but will not throw as large an amount of water as when the opening is larger.

In Fig. 3 I have represented a pump and cooler that may be placed in any position required, and has only one opening to the water through the hull of the boat.

By placing valves in the legs G G the water can be shut off to drain the cooler in cold weather.

Having thus fully described my invention, what I claim as new, and desire to secure by Letters Patent, is—

1. The arrangement, with the head of a steam-pump, of the discharge-pipes B B' and steam-jet pipe C, the pipe B passing centrally across the head to the steam-jet pipe, substantially as and for the purposes herein set forth.

2. The cooler E, provided with hollow legs G G and surrounding the discharge-pipe B', substantially as and for the purposes herein set forth.

3. The attachments H, I, and J, for the purposes herein set forth.

In testimony that I claim the foregoing I have hereunto set my hand this 30th day of May, 1872.

WM. ARTHUR.
